UNITED STATES PATENT OFFICE

2,601,111

FOLDABLE COT FOR INFANTS

Alfred Edward Foster, Birmingham, England

Application December 23, 1948, Serial No. 66,940
In Great Britain October 7, 1948

2 Claims. (Cl. 5—98)

1

This invention has reference to a foldable cot for infants. It has for its object to provide a cot which can be readily dismantled to achieve advantages in storage and transport and which can be easily collapsed for storing when not required for use.

According to the present invention a cot comprises a rectangular sectional frame and a flexible hammock slung therefrom, the said frame comprising uprights and longitudinal and lateral members detachably mounted on the uprights and adapted to be fixed together as a rigid structure, the said frame being collapsible into a parallelogram with the hammock in position when the fixing is released.

Preferably, the said frame is composed mainly of tubes or rods of which upper longitudinal and lateral members have a plug and socket engagement with the upper ends of the uprights, and similar lower members thread over the uprights up to adjustable abutments, the said upper members being fixable to the uprights by screwthread clamping devices.

According to an embodiment of the invention, the upper end of each upright is provided with a screwthreaded shank and a stop collar and each end of the longitudinal and lateral upper members with a cross bored lug to fit over said shanks up to the stop collars. Nuts, threading on said shanks, are adapted to clamp the members to the uprights.

Additional longitudinal and lateral members with cross bored end lugs are adapted to be slidably engaged over said uprights in superposed order and to be retained between the ends thereof by means of india rubber or like elastic collars gripping the uprights so that said collars form abutments above and below the superposed lugs of adjoining longitudinal and lateral members and thus hold them against vertical displacement.

The lower ends of the uprights are provided with detachable india rubber or like feet.

The said nuts may be operated either by hand or by the use of a simple hand tool so that either the frame can be rigidly secured in rectangular form or can be collapsed into the form of a parallelogram.

In the accompanying drawing an embodiment of the invention is illustrated by way of example and will now be described with reference thereto. In the drawing:

Fig. 1 is a perspective view of an infant's cot assembled for use.

Fig. 2 is a side elevation of the cot when collapsed.

2

Fig. 3 is a topside diagrammatic plan of Fig. 2, the hammock being omitted for the purpose of illustration.

Fig. 4 is an exploded view of an upper end of the sectional frame.

Fig. 5 is a fragmentary perspective view of a lower part of the said frame, and

Fig. 6 is a sectional view of Fig. 5.

The cot illustrated comprises four steel uprights 1 of uniform length, the upper ends having screwthreaded shanks 2 and the lower ends being fitted with detachable socket type feet 3 made of india rubber or substitute. The said uprights 1 are interconnected and formed into an oblong sectional frame by means of upper longitudinal and lateral members 4, 5, and lower longitudinal and lateral members 6, 7, arranged in superposed order. The ends of all the members 4, 5, 6 and 7 are formed with bored cross lugs 8 forming sleeves which slidably engage over the uprights 1 up to abutments, the latter for the lower members 6, 7, being provided by india rubber collars 9 which frictionally grip the exterior of the uprights 1 and hold the members 6, 7, in the position desired and which can be removed forcibly. The members 6, 7, carry no load and are employed to stiffen the structure. A flexible hammock 10, of strong textile material, is slung from the upper members 4, 5, for which purpose the hammock has boundary hems 11 furnishing sleeves 12 through which the upper members 4, 5, are threaded; a miniature removable mattress 13 is provided to maintain the outline of the hammock 10. The sectional structure is made rigid by tightening the nuts 14 on the screwed shank 2 when the lower lugs 8a are pressed against the abutments 15 and the upper lugs 8b are clamped against the lower lugs 8a—see Fig. 4. These nuts can be tightened and loosened by means of a small tommy bar or other shanked tool inserted in the lateral hole 16 provided in the head of each nut. In this position of fixing, the cot is quite rigid and capable of accommodating an infant without risk of accident in the ordinary course of use.

When it is desired to stow the cot as a temporary measure, which may be required from time to time, especially where accommodation is restricted as in small flats or in the many instances of overcrowding in homes, it is merely required that the four nuts 14 be slackened to enable the members 4, 5, to be free about the uprights 1 and of the structure being collapsed folded into a parallelogram as seen in Figs. 2 and 3, the mattress 13 being raised either into a vertical plane in the hammock 10, or it can be

removed. Apart from the important advantage of stowing above described, the cot has an added benefit that it can be readily dismantled. This is effected simply by removing the nuts 14, disconnecting the bored lugs 8, 8, from the threaded shanks 2, removing the hammock 10 from the upper members 4, 5, disconnecting the feet 3 and collars 9 and then sliding the members 6, 7, towards the base out of engagement with the uprights 1. The disconnected components can then be placed in a box which provides a ready and simple means for storage and transport which is an important advantage not only when dealing with such cots in bulk, but for individuals making a journey with an infant where the importance of having cot facilities on arrival cannot be under estimated.

The sectional structure illustrated consists of members 4, 6, measuring in length thirty-five (35) inches, members 5, 7, eighteen (18) inches and uprights 1 of thirty-two (32) inches and when dismantled the entire cot can be packed in a box measuring thirty-six inches by four inches by three-and-a-half inches (36" x 4" x 3½"). The erection and dismantling of the cot can be carried out by an unskilled person in but a few minutes and the adjustment for the purpose of stowing in a few seconds.

It will, therefore, be appreciated that I have provided a cot which is simple and effective and which can be erected or dismantled and stowed quickly without the exercise of skill or labour and while I have described the preferred embodiment of the invention I desire not to be restricted by that embodiment as various modifications may be made without departing from the spirit of the invention as defined by the following claims.

What I claim is:

1. A cot comprising a rectangular frame including uprights and an upper set and a lower set of longitudinal and lateral members mounted on said uprights, each set of members having sleeved ends slidably engageable with said uprights in superposed order, removable abutments for the lower set of members, said abutments consisting of elastic collars contracting on said uprights, screw clamping means between the upper ends of the uprights and the said upper set of members for detachably securing the latter to the said uprights and for permitting, when the clamping means is released, of the frame being folded into a parallelogram, and a hammock slung from the upper set of members.

2. A cot according to claim 1 and including a screwthreaded shank at the upper end of each upright and nuts engaging said shanks, each said nut having a lateral hole therein into which a hand tool shank can be inserted.

ALFRED EDWARD FOSTER.
